(57) **CLAIM**

The ornamental design for an orthopedic device, as shown and described.

DESCRIPTION

FIG. 1 is a perspective view of an orthotic device in a closed configuration.

FIG. 2 is a second perspective view of the orthopedic device according to the embodiment of FIG. 1.

FIG. 3 is a front elevational view according to the embodiment of FIG. 1.

FIG. 4 is a rear elevational view according to the embodiment of FIG. 1.

FIG. 5 is a first side elevational view according to the embodiment of FIG. 1.

FIG. 6 is a second side elevational view according to the embodiment of FIG. 1.

FIG. 7 is a top plan view according to the embodiment of FIG. 1.

FIG. 8 is a bottom plan view according to the embodiment of FIG. 1.

FIG. 9 is a perspective view of an orthotic device in an open configuration.

FIG. 10 is a second perspective view of the orthopedic device according to the embodiment of FIG. 9.

FIG. 11 is a front elevational view according to the embodiment of FIG. 9.

FIG. 12 is a rear elevational view according to the embodiment of FIG. 9.

FIG. 13 is a first side elevational view according to the embodiment of FIG. 9.

FIG. 14 is a second side elevational view according to the embodiment of FIG. 9.

FIG. 15 is a top plan view according to the embodiment of FIG. 9; and,

FIG. 16 is a bottom plan view according to the embodiment of FIG. 9.

The closely spaced line shading in FIGS. 9-14 illustrates the flattened orientation of the straps.

The broken lines illustrate environmental structure of the orthotic device and form no part of the claimed design.
